DESIGN.

—o—

J. L. FOLSOM.

CARPET.

No. 17,623.

Patented Aug. 9, 1887.

UNITED STATES PATENT OFFICE.

JAMES L. FOLSOM, OF BROOKLYN, NEW YORK, ASSIGNEE TO THE HARTFORD CARPET COMPANY, OF HARTFORD, CONNECTICUT.

DESIGN FOR A CARPET.

SPECIFICATION forming part of Design No. 17,623, dated August 9, 1887.

Application filed July 6, 1887. Serial No. 243,563. Term of patent 30 years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 My design consists, mainly, of a compact

mass of coral shaped figures having their edges ornamented with a pebble or bead work. The mass of each figure is ornamented here and there with separate blocks or geometrical forms. These figures are placed upon a ground-work in which occur at uneven intervals similarly shaped geometrical forms.

What I claim as new, and desire to secure by Letters Patent, is—

The design for carpets, consisting of the design substantially as shown.

JAS. L. FOLSOM.
